UNITED STATES PATENT OFFICE

161,975

PORTABLE REFRIGERATOR

Brinzie A. Thomaras, Detroit, Mich.

Application February 9, 1949, Serial No. 924

Term of patent 14 years

(Cl. D67—3)

To all whom it may concern:

Be it known that I, Brinzie A. Thomaras, a citizen of the United States of America, residing in Detroit, in the county of Wayne, State of Michigan, have invented a new, original, and ornamental Design for a Portable Refrigerator, of which the following is a specification, reference being had to the accompanying drawing, forming a part thereof, wherein:

Figure 3 is a perspective view of the same, showing the bottom thereof, the other side, and the other end.

I claim:

The ornamental design for a portable refrigerator, as shown.

BRINZIE A. THOMARAS.
